GAME BOARD

Jay Ward, Box 214, Huron, Ohio

Filed July 25, 1963, Ser. No. 75,954

Term of patent 14 years

(Cl. D34—5)

The figure is a top plan view of a game board showing my new design.

The dominant features of my design reside in the portions shown in full lines.

The board is of conventional thickness and the bottom and side portions not shown are substantially plain.

I claim:

The ornamental design for a game board, substantially as shown and described.
